UNITED STATES PATENT OFFICE.

EMIL P. RAETHER, OF NEW YORK, N. Y.

BOTTLE-STOPPER.

SPECIFICATION forming part of Letters Patent No. 230,054, dated July 13, 1880.

Application filed April 28, 1880. (Model.)

To all whom it may concern:

Be it known that I, EMIL P. RAETHER, of the city, county, and State of New York, have invented a new and Improved Bottle-Stopper, 5 of which the following is a specification.

The invention consists of a bottle-stopper formed of a cork, a flanged tube provided with a stud and an eccentric notched collar, a plate pivoted to the said collar, a flanged and spirally-slotted sleeve provided with an eccentric collar carrying an upwardly-projecting pin, and a spring interposed between the flanges of the tube and sleeve, as will be hereinafter more fully described, and specified in the claims.

15 Figure 1 is an elevation of the device closed. Fig. 2 is a sectional elevation of the same on line *x x*. Fig. 3 is an elevation of the device open. Fig. 4 is a plan of the device open. Fig. 5 is a plan view of the device closed.

20 Similar letters of reference indicate corresponding parts.

In the drawings, A represents a cork. B is the tube passed perpendicularly through the cork A and extending above it, and provided 25 with an annular downward-sloping flange, *a*, that fits upon the cork A and covers the lip of the bottle. A stud, *b*, projects laterally from the said tube B, and encircling the top of said tube is an eccentric collar, *c*, one of 30 whose edges is notched, as shown at *d*.

C is a sleeve having about its lower end an annular downward-sloping flange, *f*, whose rim extends downward when the stopper is closed nearly in contact with the flange *a* of the tube 35 B, and thereby prevents the ingress of flies between the two flanges. This sleeve C is provided with a spiral slot, *g*, extending upward from the flange *f* and about an eighth of the way around said sleeve, and in this slot *g* 40 the stud *b* of the tube B engages.

About the top of the sleeve C is secured an eccentric collar, *h*, corresponding with the collar *c* of the tube B, and being parallel with and beneath it, and from the outer end of this 45 collar *h* a pin, *m*, projects upward through the notch *d* of the tube-collar *c*, which notch *d* permits the collars *c h* to lie parallel with each other by admitting the pin *m*.

On the upper face of the tube-collar *c* is centrally pivoted a plate, *D*, whose inner end is designed to cover or close the end of the tube B, and through whose outer end the pin *m* of the sleeve C projects upward.

Between the flanges *a f* of the tube B and 55 sleeve C, respectively, is a spring, *E*, that op-

erates to press the sleeve C upward, and thereby keep the plate D over the top of the tube B.

When this stopper is in a bottle with its several parts in the position as shown in Figs. 1 and 2 the bottle is securely corked, so that 60 none of its contents can escape, the sleeve C being pressed upward by the spring *E*, so that the plate D is held over and firmly down upon the top of the tube B.

To open the stopper the operator presses 65 down upon the flange *f* of the sleeve C, when said sleeve C is thereby drawn downward and at the same time turned partly around on the stud *b* of the tube B, and thereby the plate D is turned on its pivot by means of the engagement of the pin *m* in the said plate, so that the inner end of said plate D is turned aside from the top of the tube B, as shown in Figs. 3 and 4, to permit the escape of the contents of the bottle; and on removal of pressure from the 75 flange *f* the said sleeve C and plate D are restored to their primary positions by the action of the spring *E*.

This device is especially adapted to bottles containing sirups, bitters, and other fluids 80 used in restaurants.

Having thus described my invention, I claim as new and desire to secure by Letters Patent—

1. As an improved article of manufacture, a 85 bottle - stopper constructed substantially as herein shown and described, consisting of cork A, flanged tube B, provided with stud *b* and with eccentric notched collar *c*, flanged sleeve C, provided with spiral slot *g* and eccentric 90 collar *h*, having a pin, *m*, pivoted plate D, and spring *E*, as set forth.

2. In a bottle-stopper, the combination, with the tube B, provided with the stud *b* and the eccentric notched collar *c*, carrying the pivoted plate D, of the spirally-slotted sleeve C, provided with the eccentric collar *h*, carrying pin *m*, substantially as and for the purpose set forth. 95

3. In a bottle-stopper, the combination, with the tube B, provided with the flange *a*, the stud *b*, and the eccentric notched collar *c*, carrying the plate D, of the spirally - slotted sleeve C, provided with the flange *f* and eccentric collar *h*, carrying pin *m*, and the spring *E*, 105 substantially as and for the purpose set forth.

EMIL P. RAETHER.
